(57) **CLAIM**

The ornamental design for an electrocardiograph, as shown and described.

DESCRIPTION

1. Electrocardiograph

1.1 : Perspective

1.2 : Perspective

1.3 : Front

1.4 : Back

1.5 : Left

1.6 : Right

1.7 : Enlarged top view

1.8 : Enlarged bottom view

1.9 : Partial enlarged view of portion 9 in FIG. 1

1.10 : Partial enlarged view of portion 10 in FIG. 1

1.11 : Partial enlarged view of portion 11 in FIG. 2

The product is used to collect electro-cardio signals; The numbers 9, 10, 11, and dashed-dotted lines in reproduction 1.1 and 1.2 indicate the enlarged portions shown in reproductions 1.9-1.11 and do not form part of the claimed design. The even length broken lines show portions of the electrocardiograph that form no part of the claimed design.
